CLAIM

The ornamental design for a combined collapsible copy holder stand and right therefor, as shown and described.

DESCRIPTION

FIG. 1 is a top, left front perspective view of a combined collapsible copy holder stand and light therefor showing my new design in a partially extended position; FIG. 2 is a left side elevational view with the document holding member in a fully extended position, the right side being a mirror image thereof;

FIG. 3 is a front elevational view of FIG. 2;

FIG. 4 is a top plan view drawn to an enlarged scale, with the document holding member in a collapsed position;

FIG. 5 is a left side elevational view of FIG. 4, the right side being a mirror image thereof;

FIG. 6 is a bottom plan view of FIG. 4;

FIG. 7 is a rear elevational view of FIG. 4; and,

FIG. 8 is a front elevational view of FIG. 4.
